US0D1077411S

(12) **United States Design Patent** (10) **Patent No.:** **US D1,077,411 S**
(45) **Date of Patent:** **** May 27, 2025**

(54) **DUSTBIN**

(71) Applicant: **Top Profit Manufacturing Co., Ltd.**,
Foshan (CN)

(72) Inventor: **Kin Wing Cheung**, Hong Kong (CN)

(73) Assignee: **Top Profit Manufacturing Co., Ltd.**,
Foshan (CN)

(**) Term: **15 Years**

(21) Appl. No.: **29/909,518**

(22) Filed: **Aug. 7, 2023**

(30) **Foreign Application Priority Data**

Apr. 7, 2023 (CN) 202330185115.2

(51) **LOC (15) Cl.** **09-09**

(57) **CLAIM**

The ornamental design for a dustbin, as shown and described.

DESCRIPTION

FIG. 1 is a top, front, left-side perspective view of a dustbin according to a first embodiment of the present disclosure;

FIG. 2 is a top, rear, left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and

FIG. 8 is a bottom plan view thereof;

FIG. 9 is a top, front, left-side perspective view of a dustbin according to a second embodiment of the present disclosure;

FIG. 10 is a top, rear, left-side perspective view thereof;

FIG. 11 is a front elevational view thereof;

FIG. 12 is a rear elevational view thereof;

FIG. 13 is a left-side elevational view thereof;

FIG. 14 is a right-side elevational view thereof;

FIG. 15 is a top plan view thereof; and,

FIG. 16 is a bottom plan view thereof.

The broken lines shown in the drawings depict portions of the dustbin that form no part of the claimed design.

1 Claim, 16 Drawing Sheets
